UNITED STATES PATENT OFFICE

JOSEF FRICKE, OF DILLINGEN-SAAR, GERMANY

STEREOPRINTING BLOCK

Application filed November 12, 1929, Serial No. 406,548, and in Germany May 22, 1929.

The use of large, for instance full page, stereo blocks for repeat work in printing, involves difficulties in that the wooden base of such a block, even if made of the very best 5 seasoned wood, becomes warped and in time it is necessary to straighten it and refit it, which work is difficult and takes a long time.

This invention is intended to avoid the said drawback and consists in using an iron 10 backing plate which is lined with wood at the back in order to afford a hold to the nails which must be driven in.

The new backing plate for large blocks is shown in the accompanying drawings in 15 which—

Figure 1 is a plan,

Figure 2 is a back view, and

Figure 3 is a cross section through the plate on the line A—B in Figure 2.

20 Figures 4 and 5 are respectively a plan and elevation of a template employed when using the backing plate.

a is an iron plate which is provided on the back with ribs *b*, *c* which rest on a support 25 in the printing press. Its upper face is flat and is intended to support if desired with the interposition of a layer of paper, the stereo marked *d* in Figure 3.

In order to enable the stereo to be secured 30 to the iron plate, the latter is provided all over in a uniform manner with holes *e* for nails to be driven through. In Figures 1 and 2, these holes are shown only on one quarter of the plate, but the other parts of the 35 plate are also provided with such holes.

In order to afford a good hold to the nails driven through the stereo and the holes of the iron plate, the latter between the ribs *b*, *c* is backed with wood *f* which however is of 40 no importance as regards the shape of the plate. The holes *e'* which are situated on the ribs, are drilled obliquely so that the nails can still grip the wood in an effective manner as may be seen from Figure 3.

45 It might be difficult to hit exactly the holes in the plate *a* with nails driven through the stereo, and in order to facilitate this a template *g* of sheet metal is used which covers one quarter of the plate *a* and is provided 50 at one side with registering pins *h* which

fit into holes *i* in the plate *a*. Obviously holes for the said pins *h* must be provided also in stereos which are larger than one quarter of the plate *a*. The template *g* is provided with holes *k* of the same number 55 and arrangement as those in the plate *a*, so that the holes of the template and of the plate *a* coincide exactly. If therefore a stereo is to be secured to the plate, it is placed on the latter in such a manner that its holes coincide with the holes *i*, and the template is put on so that its pins *h* enter the holes *i*. It is then possible to mark the nail holes in 60 the stereo by means of the template and thus it is always possible to find the holes in the plate *a* when driving in the nails.

As the stereos are secured to such a backing plate only during the printing operation, whilst otherwise they are stored without the plate a few such backing plates will be sufficient for one printing machine. No warping 65 of the backing plate and therefore of the stereo can take place.

Having now particularly described and ascertained the nature of our said invention and in what manner the same is to be performed, I declare that what I claim is:—

1. A backing for stereotypes, comprising an iron plate provided on its back surface with ribs adapted to rest on a support in 70 a printing press, said ribs being disposed so as to divide the back surface of the plate into a plurality of separated compartments, and a wooden block disposed in each of said compartments in snug engagement with its 75 bounding ribs, said plate being provided throughout its area with a plurality of perforations for the passage of means for securing the stereotypes to the wooden blocks.

2. In combination, a backing for stereotypes as set forth in claim 1, and a sheet metal template provided with perforations adapted to register with those of the iron plate.

3. In combination, a backing for stereotypes as set forth in claim 1, a sheet metal template provided with perforations adapted to register with those of the iron plate, and cooperating means carried by said template and plate for ensuring registration.

JOSEF FRICKE.
